UNITED STATES PATENT OFFICE.

ALBERT N. STOLLWERCK, OF JERSEY CITY, NEW JERSEY.

DESIGN FOR A CHOCOLATE CAKE.

52,246.

Specification for Design.

Patented July 30, 1918.

Application filed February 2, 1918. Serial No. 215,212. Term of patent 7 years.

To all whom it may concern:

Be it known that I, ALBERT N. STOLLWERCK, a citizen of the United States, residing at Jersey City, in the county of Hudson and State of New Jersey, have invented a new, original, and ornamental Design for a Chocolate Cake, of which the following is a specification, reference being had to the accompanying drawing, forming part thereof.

Figure 1 is a plan view of a chocolate cake showing my new design;

Fig. 2 a side view;

Fig. 3 a longitudinal section on line 3—3 Fig. 1, and

Fig. 4 a cross section on line 4—4 Fig. 1. The design comprises a plurality of convex sections 1, which are arranged sidewise of each other. Each section is provided with a pair of sunk panels 2, bound by a pair of longitudinal rims 3, a pair of arched transverse rims 4, formed at the ends of sections 1, and additional arched transverse rims 5, extending across said sections, intermediate of the end rims 4.

I claim:

The ornamental design for a chocolate cake, substantially as shown and described.

ALBERT N. STOLLWERCK.
